(57) CLAIM

The ornamental design for a pot lid, as shown and described.

DESCRIPTION

FIG. 1 is a front elevation view of a pot lid, showing our new design;

FIG. 2 is a back elevation view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken lines shown in FIGS. 5-7 depict portions of the pot lid that form no part of the claimed design. The shade lines in the figures show contour and not surface ornamentation.
